[57] CLAIM

The ornamental design for a measuring receptacle having removable bottom with handle, substantially as shown and described.

DESCRIPTION

FIG. 1 is a perspective view of a measuring receptacle having removable bottom with handle showing my new design;

FIG. 2 is a top plan view thereof;

FIG. 3 is a side elevational view thereof;

FIG. 4 is a side elevational view thereof taken in the direction opposite to that of FIG. 3;

FIG. 5 is an end view thereof.

The bottom face of the removable bottom is planar.
